DRILL SUPPORT

Filed Sept. 20, 1945

UNITED STATES PATENT OFFICE

2,416,912

DRILL SUPPORT

Frank De Curtis, Queens Village, N. Y.

Application September 20, 1945, Serial No. 617,544

4 Claims. (Cl. 77—13)

1

This invention relates to a drill support adapted to hold an ordinary hand drill in a rigidly perpendicular position with respect to work which is clamped in a vise. It is common experience that drill bits usually break by reason of bending strains put thereon when a hand drill in which a drill bit is being used is moved out of line with the hole which is being bored by the drill bit. It is difficult for the average user of a hand drill to maintain the axis of the drill accurately in line with the hole which is being bored. An object of the present invention is to provide a support or frame adapted to be mounted upon one of the jaws of a vise, the drill being held by the support in a rigidly vertical position and being adjustable laterally so as to bring the tip of the drill bit over any desired point of the work which is clamped in the vise. The support is constructed so as to permit vertical axial movement of the drill during the drilling operation so that the drill bit can penetrate into the work.

It is an object of the invention to provide a support which is simple in structure and which is adapted to be used in combination with an ordinary hand drill such as can be purchased in any hardware store.

Other advantageous features of the drill support embodying the invention will be apparent from the following description thereof and from the drawing, of which:

Figure 1 is a perspective view of a drill support embodying the invention;

Figure 2 is a front elevation of the same with a hand drill attached, portions of the support being broken away to show in section;

Figure 3 is a section on the line 3—3 of Figure 2;

Figure 4 is a perspective view of a part of the support;

Figure 5 is a side elevation of a vise on which is mounted the drill support shown in Figure 1, the base of the support being shown in section on the line 5—5 of Figure 1;

Figure 6 is a perspective view of the base of the support.

The support illustrated in the drawing comprises a generally rectangular base 10 adapted to fit over one jaw 12 of a vise 14. The base 10 includes a top 16 which rests on the top of the jaw 12, a front wall 18 which bears against the face of the jaw 12, and end walls 20 and 22 which are adjacent to the end faces of the jaw 12. A set screw 24 is threaded through the end wall 20 of the base 10 and is set up to bear against the adjacent end face of the vise jaw so as to clamp the

2

base securely on the jaw. The set screw is preferably of substantial length to accommodate vise jaws of sizes smaller than the largest size which can be received between the end walls 20 and 22. 5 When thus secured, the top 16 of the base is preferably horizontal, and the front wall 18 of the base is vertical. As indicated in the Figure 5, a work piece W can be clamped in the usual manner between the front jaw 12 of the vise and the wall 18 of the base which bears against the face of the jaw 12.

The top 16 of the base is provided with a forwardly projecting portion 28 at one end thereof and also with spaced lugs 30 and 32, the lug 32 being at the opposite end from the extension 28. The extension 28 and the lugs 30 and 32 serve to facilitate the placing of the work in the vise in a horizontal position, the under surfaces of the extension 28 and the lugs 30 and 32 being in a common horizontal plane. The extension 28 is provided with a rail 34 which, as shown in Figures 1, 2, and 6, has undercut edges so that the rail has a dovetailed cross section. Slidably mounted on the rail 34 is a slide 36 which can be 15 secured in any desired position of adjustment along the rail by a set screw 38. Extending upward from the slide 36 is a vertical telescoping standard consisting of a rod 40, preferably of a square cross section, on which is slidably the leg portion 42 of a T-shaped tubular member having a cross arm 44 with a tubular bore in which is slidably received a horizontal rod 46. A set screw 48 may be provided to secure the T-shaped member in any desired position of vertical adjustment. 20 In like manner a set screw 50 is provided to secure the rod 46 in any position of axial adjustment. At one end of the rod 46 is a threaded stud 52 which is adapted to screw into the threaded recess in the frame of a hand drill 54 which is customarily provided for the support of a handle knob. As shown in Figure 2, when the rod 46 is screwed into the threaded recess in the drill frame, it projects therefrom horizontally and the axis of the drill is vertical. The square rod 46 fits slidably 25 in the cross arm 44 and is therefore non-rotatable therein but is an axially adjustable extension thereof. By adjustably moving the slide 36 on the rail 34 and adjustably moving the rod 46 in the cross arm 44, the drill bit 56 can be brought over any desired point of the work W. The screws 38 and 50 may then be set up to maintain the drill bit 56 over such point. The screw 48 is then backed off sufficiently to allow the T member and the drill to move vertically downward to bring the drill bit 56 into operative contact with the work

W. Rotation of the drill bit by manipulation of the handle 58 will then cause the bit to bore into the work, the jig serving to keep the drill accurately in line with the hole which is formed in the work by the drill bit 56.

It is evident that various modifications of details of the invention herein described can be made without departing from the spirit or scope thereof, as defined in the following claims.

I claim:

1. A device of the class described comprising a base adapted to be clamped to one jaw of a vise, a horizontal rail on said base, a slide movable along said rail, means for clamping said slide to said rail, a telescoping standard mounted on said slide, a non-rotatable horizontal rod mounted on said standard at its upper end and axially adjustable thereon, and a hand drill secured to one end of said rod with its axis parallel to said standard.

2. A drill support comprising a base adapted to be clamped on one jaw of a vise, a horizontal rail on said base, a slide adjustably secured to said rail, a vertical telescoping standard on said slide, a horizontal sleeve at the upper end of said standard, and a rod non-rotatably mounted in said sleeve and axially adjustable therein, said rod having means at an end thereof for securing a hand drill thereto.

3. A drill support comprising a base adapted to be clamped on one jaw of a vise, a horizontal rail on said base, a slide adjustably secured to said rail, a vertical rod of square cross-section

mounted on said slide, a T-shaped tubular member having leg and cross-arm portions, said member telescoping said rod in its leg portion and having a square bore through its cross-arm portion, a horizontal rod of square cross-section slidably fitted in said cross-arm bore, and means on an end of said horizontal rod to make a rigid connection with a hand drill.

4. In combination with a vise adapted to hold work between the jaws thereof, a drill support comprising a base clamped to one of said jaws, a vertical standard mounted on said base and laterally adjustable thereon, a horizontal cross-arm mounted on said standard and vertically adjustable thereon, an extension non-rotatably mounted on said cross-arm and axially extensible, and a hand drill rigidly secured to an end of said extension with its axis parallel to said standard.
